(57) **CLAIM**

The ornamental design for a surface configuration of a wristwatch, as shown and described.

DESCRIPTION

FIG. 1 is a front view of a surface configuration of a wristwatch according to my novel design;

FIG. 2 is a right side view of a surface configuration of the wristwatch according to my novel design; and,

FIG. 3 is a perspective view of a surface configuration of the wristwatch according to my novel design.

The dash lines included depict environment and are not part of the claimed design.

1 Claim, 2 Drawing Sheets

FIG. 3
